(57) **CLAIM**

The ornamental design for a wall-mount paper towel holder, as shown and described.

DESCRIPTION

FIG. 1 is a perspective view of a wall-mount paper towel holder showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken-line disclosure of elements in the views is for illustrative purposes only and forms no part of the claimed design.
